UNITED STATES PATENT OFFICE.

CHARLES HAMMELMANN, OF BUFFALO, NEW YORK.

MECHANICAL MOVEMENT.

SPECIFICATION forming part of Letters Patent No. 339,547, dated April 6, 1886.

Application filed October 26, 1885. Serial No. 120,930. (No model.)

To all whom it may concern:

Be it known that I, CHARLES HAMMELMANN, of the city of Buffalo, in the county of Erie and State of New York, have invented a new and 5 useful Improvement in Mechanical Movements, of which the following is a specification.

This invention relates to an improvement in that class of mechanical movements which are employed for converting the reciprocating or 10 oscillating motion of a hand-lever or treadle into a rapid rotary motion, and which are more especially employed for operating the rotary blowers of portable forges and other revolving instruments or devices which require 15 a high rotary speed.

The object of my invention is to produce an efficient and compact mechanism of this kind which will produce the desired result in a very simple and direct manner; and my invention 20 consists, to that end, of the improvements which will be hereinafter fully set forth, and pointed out in the claims.

In the accompanying drawings, consisting of two sheets, Figure 1 is a side elevation of a 25 portable forge provided with my improved mechanical movement. Fig. 2 is a horizontal section, on an enlarged scale, through the handle of the driving-wheel. Fig. 3 is a vertical section in line xx , Fig. 2. Fig. 4 is a vertical section in line yy , Fig. 3. Fig. 5 is a cross-section in line zz , Fig. 4. Fig. 6 is a face view of the loose part of the clutch. Fig. 7 is a cross-section of the hand-lever support on an enlarged scale.

35 Like letters of reference refer to like parts in the several figures.

A represents the bowl or hearth of a portable forge, supported on legs a , and provided with a hood, a' . B represents the blower or 40 fan, secured to the lower side of the bowl A, and provided with a suitable pulley on its shaft. All of these parts are constructed in any suitable or well-known manner.

C represents the driving - wheel, connected 45 with the pulley on the blower-shaft by an endless belt, c , and mounted loosely on an arbor, d , which is supported in the frame of the machine, and preferably made adjustable by set-screws d' , for tightening the belt c when required.

E represents a cylindrical neck or collar

formed on one side of the hub of the wheel C, and F is a serrated or toothed clutch - disk formed on or secured to the outer end of the neck E, with its toothed side turned toward 55 the wheel C.

G represents a clutch-disk mounted loosely on the neck E, with the toothed side adjacent to the toothed side of the disk F. The latter is preferably cast in one piece with the neck 60 E, and the disk G is made in two parts, which are secured together by screws g , after being applied to the neck E, as represented in Fig. 6. The teeth on the adjacent sides of the disks F and G are made inclined, so that upon turning the loose disk G forwardly in the direction of the arrow in Fig. 2 the motion of the loose disk will be transmitted to the disk F, while upon turning the loose disk in an opposite direction the disk F and the wheel C, secured 70 thereto, will continue their forward movement, notwithstanding the reversal of the movement of the disk G.

h represents projecting lugs or ears formed on the periphery of the disk G.

H is a cylindrical collar or sleeve, which encloses the clutch-disks F and G, and which is provided with a neck, i . The latter turns loosely on the arbor d , and is provided at its outer end with a gear-pinion, J. The sleeve 80 H is provided with inclined slots or ways j , in which the lugs h of the loose clutch - disk G engage, so that by turning the sleeve H forwardly the inclined slots j , acting upon the lugs h , will throw the loose disk G in engagement with the disk F, and upon reversing the motion of the sleeve H the loose disk G will be moved out of engagement with the disk F. An alternating forward and backward rotary motion is imparted to the sleeve H by a vertical reciprocating rack-bar, K, which engages 85 with the pinion J. The rack-bar is arranged in a casing, L, in which it is guided by vertical ribs l . The casing L is secured to the stationary frame of the machine by screws m , or 90 in any other suitable manner.

N represents the pivoted hand-lever, which is connected with the rack-bar K by a rod, O. The latter is attached to the rack-bar and the hand-lever by eyes $p p'$, which permit of a sufficient lateral movement of the hand-lever to 95 allow the operator the requisite freedom of

movement for reaching tools, &c., while operating the blower. The hand-lever N is pivoted by a horizontal bolt, q, to a bifurcated support, R, which in turn is pivoted to the 5 supporting-standard S by a vertical bolt, s, as represented in Fig. 7, so that the hand-lever can be turned horizontally and vertically. Any other universal joint—for instance, a ball-and-socket joint—may, however, be employed, if 10 preferred.

Upon pressing the free end of the hand-lever downward, the rack-bar K is raised, and the pinion J and sleeve H are rotated forwardly in the direction of the arrow in Fig. 2, where- 15 by the loose clutch-disk G is thrown in engagement with the disk F, and the latter and the driving-wheel C are turned forwardly in the proper direction for operating the blower. On the reverse stroke of the hand-lever, the rack- 20 bar K descends, the pinion J and sleeve H are rotated in an opposite direction, the clutch-disk G is moved out of engagement with the disk F and turned in an opposite direction, while the wheel C and connecting parts con- 25 tinue their forward rotation by the momentum imparted to the parts during the effective stroke of the hand-lever. In this manner the easy up-and-down motion of the hand-lever is converted into a rapid rotary motion of the 30 driving-wheel and blower, without requiring any counter-shafts or multiplying gears or pul-leys. The blower or other rotating part can only be rotated in the right direction, irre- 35 spective of the position of the hand-lever when the movement is begun, and the machine can- not stop at a dead-center, so that the machine is always ready to be set in motion by simply operating the hand-lever. By increasing or decreasing the stroke of the hand-lever the 40 speed of the blower is increased or decreased, and the hand-lever may at times be held sta- tionary, with the clutch-disk G disengaged from the disk F, without interfering with or arresting the rotary motion of the blower.

45 I claim as my invention—

1. The combination, with a driving-wheel, C, provided with a clutch-disk, F, of a loose clutch-disk, G, which is turned alternately backwardly and forwardly, and which is thrown in engage- 50 ment with the disk F on its forward movement

and out of engagement on its backward move- ment, substantially as set forth.

2. The combination, with a driving-wheel, C, provided with a clutch-disk, F, of a loose clutch-disk, G, and a collar, H, which is turned alter- 55 nately backwardly and forwardly, and which throws the disk G alternately in engagement and out of engagement with the disk F, sub- stantially as set forth.

3. The combination, with the driving-wheel 60 C, provided with a clutch-disk, F, of a loose clutch-disk, G, provided with lugs h, and a collar, H, provided with inclined guides j, in which the lugs h engage, substantially as set forth.

4. The combination, with the driving-wheel 65 C, provided with a clutch-disk, F, of the loose clutch-disk G, a collar, H, connected with the disk G, and provided with a pinion, J, and a reciprocating rack-bar, K, engaging with the pinion J, substantially as set forth.

5. The combination, with the driving-wheel 70 C, provided with a clutch-disk, F, of a loose clutch-disk, G, a collar, H, connected with the disk G, and provided with a pinion, J, a rack- 75 bar, K, engaging with the pinion J, a hand- lever, N, and a rod, O, connecting the rack-bar with the hand-lever, substantially as set forth.

6. The combination, with a rotary blower, B, of a driving-wheel, C, provided with a clutch- 80 disk, F, a loose clutch-disk, G, and a col- ller, H, connected with the disk G, and turned alternately backward and forward, substan- tially as set forth.

7. The combination, with the driving-wheel 85 C, provided with a clutch-disk, F, of a loose clutch-disk, G, a collar, H, provided with a pinion, J, a rack-bar, K, and a casing, L, in- closing the rack-bar and provided with guides 90 l, substantially as set forth.

8. The combination, with the wheel C, cast 95 with a neck, E, and clutch-disk F, of the loose clutch-disk G, made in halves and mounted on the neck E by securing the halves together, substantially as set forth.

Witness my hand this 22d day of October, 1885.

CHARLES HAMMELMANN.
